UNITED STATES PATENT OFFICE.

HUGH S. KERR, OF PHILADELPHIA, PENNSYLVANIA.

DESIGN FOR A TOY-SLIPPER BLANK.

SPECIFICATION forming part of Design No. 26,612, dated February 9, 1897.

Application filed September 25, 1896. Serial No. 607,005. Term of patent 7 years.

To all whom it may concern:

Be it known that I, HUGH S. KERR, a citizen of the United States, residing in Philadelphia, Pennsylvania, have invented a certain new and useful Design for Toy Slippers, of which the following is a specification.

My design for a toy slipper is fully illustrated in the accompanying drawing.

The essential feature of the design is the blank or pattern in the form of a star, and, as shown in the accompanying drawing, a a' a'' are the points of the star, and on each side of the point a are triangular wings b b' . One of these wings has a section b' , imitating lac-

cated. The face of the blank can be decorated in any manner without departing from the essential feature of my invention.

I claim—

The design for a toy-slipper blank as herein described and shown in the accompanying drawing.

In testimony whereof I have signed my name to this specification in the presence of two subscribing witnesses.

HUGH S. KERR.
